[57] CLAIM

The ornamental design for an infant's toilet chair, substantially as shown.

DESCRIPTION

FIG. 1 is a perspective view taken from the front and left side of an infant's toilet chair embodying my new design;

FIG. 2 is a right side elevational view thereof;

FIG. 3 is a front elevational view thereof;

FIG. 4 is a rear elevational view thereof; and

FIG. 5 is a top plan view thereof.
